UNITED STATES PATENT OFFICE.

FRIDOLIN SCHIMMEL, OF FARIBAULT, MINNESOTA.

EXTENSIBLE-LEAF TABLE.

Application filed July 10, 1922. Serial No. 573,863.

To all whom it may concern:

Be it known that I, FRIDOLIN SCHIMMEL, a citizen of the United States, residing at Faribault, in the county of Rice and State of Minnesota, have invented certain new and useful Improvements in Extensible-Leaf Tables; and I do hereby declare the following to be a full, clear, and exact description of the invention, such as will enable others skilled in the art to which it appertains to make and use the same.

My invention provides an extremely simple and highly efficient extensible leaf table adapted generally for use wherever a simple extension table is desired, and particularly adapted for use as a card table, kitchen table or dining table. It may be made up cheaply where a cheap table is desired and may be made of better wood and better finish where a high grade table is desired.

In the accompanying drawings, which illustrate the invention in its preferred embodiment, like characters indicate like parts throughout the several views.

Referring to the drawings:

Fig. 1 is a perspective showing the table with its leaves extended;

Fig. 2 is a perspective showing the table with its leaves folded;

Fig. 3 is a section on the line 3—3 of Fig. 1;

Fig. 4 is a section on the line 4—4 of Fig. 2;

Fig. 5 is a horizontal section on the line 5—5 of Fig. 3, looking from the bottom upward;

Figs. 6 and 7 are fragmentary perspectives showing details; and

Fig. 8 is a fragmentary section on the same line as Fig. 3, but showing one of the leaves slightly separated from the table top proper.

The table top proper, indicated by the numeral 9, is directly secured to a table top frame 10 that is supported by suitable legs 11. The extension leaves 12 are preferably of one-half the width of the table top 9 and may be of the same length or of slightly

greater length, but, as shown, are of slightly greater length and are provided with depending marginal end strips 13 and outer edge strips 14. When the end strips 13 are employed, they are so located that when the leaves 12 are slid onto the table top 9, there

will always be clearance between said end strips 13 and the end edges of the table top.

For supporting the extension leaves 12, I provide slides, which, as shown, are in the form of three-sided racks 15, the parallel arms of which racks are arranged to slide in runways formed on the bottom of the table top 9 by means of rabbeted guide rails 16 directly secured to said table top.

The leaves 12 are connected to the cross bar or outer portions of the slides 15 with freedom for limited vertical movements, so that they may be moved, at will, either into the plane of the table top, flush therewith, as shown in Figs. 1 and 3, or into positions on top of said table top, as shown in Figs. 2 and 4. The above noted connections between the slides and leaves, as shown, are preferably made as follows:

The numeral 17 indicates metal straps 75 rigidly secured to the outer portions of the slides 15 near the corners thereof and projecting outward and provided at their projecting ends with perforations 18. The outer edge rails 14 of the leaves 12 are notched 80 at 19, and extending across these notches and secured to the under-surfaces of said straps are metal straps 20. Vertical pins 21 are extended centrally through the pockets 19 and through the perforations 18 85 of the projecting straps 17 and are secured to the straps 20 and to the leaves 12. The straps 17 being loosely secured to the bottom of the leaves and the table top and leaves being of the same thickness, it is evident that the leaves are mounted for sufficient vertical movement to bring the same 90 either into registration with or entirely above the table top. Extreme outward movements of the slides 15 and leaves 12 are 95 limited to positions shown in Fig. 8, by means of stops shown as in the form of screws 22 screwed into the under surfaces 100 of the arms of said slides and engageable with the side members of the frame 10. Here it will be noted that the said side members of the frame 10 are notched to afford 105 clearance for the arms of the slides 15.

To hold the inner edges of the leaves 12 aligned and flush with the outer edges of 105 the table top 9, the latter are shown as provided with dowel pins 23 that are engageable with the dowel pin seats 24 in the inner edges of the leaves, (see particularly Figs. 3 and 8). When the leaves are moved to 110

position above the table top, as shown in Figs. 2 and 4, a narrow table top is afforded and this top will have a neat appearance. In such adjustments, the dowel pins 23 enter 5 suitable seats in the strips 14.

From the foregoing, it is evident that the extensible leaf table described is of simple construction, has no parts that are liable to get out of order or be broken and has this 10 important feature—that, when the table top is contracted, that is, when the leaves are folded, the latter do not hang down below the frame 10, and, hence, leave all of the space below said frame clear so that a person 15 may sit in a chair with his legs under any one of the four sides of the table.

What I claim is:

1. The combination with a suitably supported table top and a slide horizontally 20 movable under the same but held against vertical movement, of an extension leaf carried by said slide but connected thereto for vertical movements so that it may, at will, be aligned with the table top or placed in 25 position on the top thereof.

2. The combination with a suitably supported table top, of a slide having arms endwise movable on the under side of said 30 table top but held against vertical movement, an extension leaf which, at its outer edge, is connected to the outer portion of said slide with freedom for vertical movements so that, at will, it may be aligned flush with said table top or positioned on 35 top thereof.

3. The combination with a suitably supported table top, of slides mounted on the under side of said table top for sliding movements in opposite directions toward and from said table top, and extension leaves 40 connected to said slides with freedom for vertical movements so that they may, at will, be aligned flush with said table top or positioned on top of the same.

4. The structure defined in claim 1 in 45 which the connections between said slide and leaf are made by metal straps secured to said slide and vertical pins passed through said straps and secured in respect to said leaf.

5. The structure defined in claim 1 in further combination with a strip on the extension leaf arranged to cover the adjacent edge of the table top when said leaf is placed on top thereof.

6. The structure defined in claim 3 in further combination with strips on the outer edges of the extension leaves arranged to cover the adjacent edges of the table top when said leaves are placed on top thereof.

7. The structure defined in claim 3 in further combination with strips on the outer edges of the extension leaves arranged to cover the adjacent edges of the table top when said leaves are placed on top thereof, 65 and at which time the inner edges of the leaves meet.

In testimony whereof I affix my signature.

FRIDOLIN SCHIMMEL.
